UNITED STATES PATENT OFFICE.

HARRY J. CRINER, OF DAVENPORT, IOWA, ASSIGNOR OF ONE-HALF TO ARTHUR G. BUSH, OF DAVENPORT, IOWA.

ADJUSTING AND REVERSING MECHANISM FOR CLOTHES WRINGERS.

Application filed January 31, 1922. Serial No. 533,047.

To all whom it may concern:

Be it known that I, HARRY J. CRINER, a citizen of the United States of America, residing at Davenport, in the county of Scott and State of Iowa, have invented certain new and useful Improvements in Adjusting and Reversing Mechanisms for Clothes Wringer, of which the following is a specification.

10 My invention relates to improvements in adjusting and reversing mechanisms for clothes wringers.

The objects of my invention are, first, to provide a simple, easily manufactured and easily controlled apparatus by which the operation of the wringer and the position of the wringer relative to the washing machine or other apparatus, may be controlled by a single lever and second, to provide a 20 simple, inexpensive apparatus to manufacture.

I attain these objects by the means illustrated in the accompanying drawings, in which—

25 Figure 1 is the side elevation of my control apparatus, showing the gears and clutch in dotted lines; Fig. 2 is a vertical section of the casing or housing of my apparatus, but showing the gears and clutch in full 30 lines, the housing being drawn in section on the line Y Y of Figure 3; Fig. 3 is a detail showing the upper part of the housing in vertical cross section and showing the attachments of the adjusting lever; Figures

35 4 and 5 are details showing the arrangements of the adjusting lever and Figure 6 is a detail view of the lower end of levers, 1 and 12, looking upward from below; Fig. 40 7 is a detail of the lever 12, and circular plate, 27, formed integral therewith.

Similar numerals refer to similar parts throughout the several views.

In my apparatus, a tube, 24, which encloses a driving shaft, is secured to the 45 washing machine or other apparatus in any manner desired. Upon the tube, 24, a housing, 2, is rotatably mounted, preferably by a sleeve, 23, extending downward into the tube, 24, or in any other suitable manner.

50 The driving shaft extends upwardly into this housing and is secured by suitable bearings mounted therein in the usual manner. Upon the upper end of the driving shaft, a bevel gear pinion, 18, is secured by being 55 keyed thereto or otherwise suitably secured.

Corresponding bevel gear pinions, 21 and 21^a, are mounted upon a shaft, 20, in constant mesh with the bevel gear pinion, 18, but are not secured to the shaft, 20. A clutch collar is splined or otherwise slidingly mounted upon the shaft, 20, with lugs, 25 and 26, extending in opposite directions therefrom, the lug, 25, corresponding to and being adapted to enter into a notch, 4, provided in the bevel gear pinion, 21^a, and the lug, 26, being adapted to enter and engage a notch, 6, formed in the bevel gear pinion, 21.

A lever, 1, is fulcrumed upon a bolt, 11, which passes through a circular plate, 10, formed integral with the lever, 1, and is secured in a similar circular plate, 27, formed integral with a lever, 12. The bolt, 11, should be set up tight enough to secure close juxtaposition of the plates, 10 and 27, but loosely enough to allow the lever, 1, to revolve upon the bolt, 11, through the arc shown in Figure 1.

The lever, 12, is fulcrumed upon a pin, 28, which passes through lugs, 9, formed integral with the housing, 2.

An opening, 7, is provided in the housing, 2, at one side thereof, which permits the entrance of the projecting lug or post, 8, formed integral with or suitably secured to the intermediate portion of the lever, 1. The inner end of the lug or post, 8, projects between the clutch collars, 19, and operates to slide the clutch upon the shaft, 20.

The upper end of the lever, 1, terminates in a handle and at the lower end of the handle, a pin, 14, is mounted bearing against a compression spring, 28. The lower end of the pin, 14, corresponds to and is adapted to enter notches, 17, formed in the top of the housing, 2, to act as detents and lock the lever, 1, into a given position longitudinally of the shaft, 20.

Lugs, 5, are formed upon the housing, 2, near the top thereof and when the lever, 1, is thrown into position to disengage the lower end of the lever, 12, from the notches, 16, in the top of the tube, 24, the upper portion of the lever, 1, will pass between the lugs, 5, and when in that position, the lugs, 5, prevent any movement of the lever, 1, longitudinally of the shaft, 20.

Likewise, when the handle of the lever, 1, is thrown to the right or left as shown in Figure 1, the lugs, 5, form a detent which

prevent the lever, 1, being thrown transversely to the housing, 2, sufficiently to disengage the latch, 12, from its seat, 16, and in this way whenever the wringer is in operation, it is locked against rotation upon the sleeve, 23.

The lower portion of the housing, 2, is provided with a collar, 13, which rests upon a corresponding collar, formed integral with 10 the upper end of the tube, 24. A notch is formed in the collar, 13, which permits the entrance of the lower end of lever, 12, therein and a plurality of notches, 16, are provided in the collar upon the upper end of 15 the tube, 24, into one of which the lower end of the lever, 12, will enter when the housing is revolved so as to bring the lever, 12, into juxtaposition to such notch.

In the description and claims, for convenience I refer to the motion of the lever, 1, as shown in Figure 1, as its longitudinal motion and to its motion as shown in Figure 4 as its transverse motion.

The bolt or set screw, 11, forms a fulcrum 25 for the longitudinal motion of the lever, 1, and the pin, 28, forms a fulcrum for the transverse motion of the lever, 1, and for the motion of latch lever, 12.

As the bolt or set screw, 11, fastens the 30 lever, 1, securely to the lever, 12, it is obvious that when the lever, 1, is operated transversely, the lever, 1, combined with the lever, 12, operate as a single lever.

It is obvious that the form and proportion 35 of the different parts of my device may be varied to a large extent without departing from the spirit of my invention.

It is also obvious that my device is applicable to many machines and appliances 40 other than wringers and I do not restrict my claims to clothes wringers.

I claim:

1. In a controlling mechanism for wringers and other machinery, the combination 45 with a shaft housing, of a gear housing rotatably mounted thereon, a latch lever fulcrumed upon the gear housing, notches cut in the upper end of the shaft housing corresponding to the lower end of the latch 50 lever and adapted to receive same, and a clutch control lever secured to the latch lever and moving simultaneously therewith when operated transversely of the housing, but secured to the latch lever by a set screw or bolt which operates as a fulcrum and allows 55 the clutch lever to be operated longitudinally of the gear housing upon the set screw as a fulcrum.

2. In a controlling mechanism for wringers and other machinery, the combination 60 with a shaft housing of a gear housing rotatably mounted thereon, gears secured upon a shaft mounted in the gear housing and a

clutch slidingly mounted upon the shaft between the gears, a latch lever fulcrumed 65 upon the gear housing, notches cut in the upper end of the shaft housing corresponding to the lower end of the latch lever and adapted to receive same, a clutch control lever secured to the latch lever and moving 70 simultaneously therewith when operated transversely of the housing, but secured to the latch lever by a set screw or bolt which operates as a fulcrum and allows the clutch lever to be operated longitudinally 75 of the gear housing upon the set screw as a fulcrum, and detents formed upon the housing which lock the clutch control lever against longitudinal motion when the latch lever is disengaged from its corresponding 80 notches or seats.

3. In a controlling mechanism for wringers and other machinery, the combination with a shaft housing of a gear housing rotatably mounted thereon, gears secured 85 upon a shaft mounted in the gear housing and a clutch slidingly mounted upon the shaft between the gears, a latch lever fulcrumed upon the gear housing, notches cut in the upper end of the shaft housing 90 corresponding to the lower end of the latch lever and adapted to receive same, a clutch control lever secured to the latch lever and moving simultaneously therewith when operated transversely of the housing, but secured to the latch lever by a set screw 95 or bolt which operates as a fulcrum and allows the clutch lever to be operated longitudinally of the gear housing upon the set screw as a fulcrum, and detents formed upon the housing which lock the clutch lever against transverse motion while the clutch is engaged with either of its adjacent gears.

4. In a controlling mechanism for wringers and other machinery, the combination 105 with a shaft housing of a gear housing rotatably mounted thereon, gears secured upon a shaft mounted in the gear housing and a clutch slidingly mounted upon the shaft between the gears, a latch lever fulcrumed 110 upon the gear housing, notches cut in the upper end of the shaft housing corresponding to the lower end of the latch lever and adapted to receive same, a clutch control lever secured to the latch lever and moving simultaneously therewith when operated transversely of the housing, but secured to the latch lever by a set screw or bolt which operates as a fulcrum and allows the clutch lever to be operated longitudinally 115 of the gear housing upon the set screw as a fulcrum, detents formed upon the housing which lock the clutch control lever against longitudinal motion when the latch lever is disengaged from its corresponding notches 120 or seats, and detents formed upon the hous- 125

ing which lock the clutch lever against transverse motion while the clutch is engaged with either of its adjacent gears.

5. In a controlling mechanism for wrenches and other machinery, the combination with a shaft housing of a gear housing rotatably mounted thereon, gears secured upon a shaft mounted in the gear housing and a clutch slidingly mounted upon the shaft between the gears, a latch lever fulcrumed upon the gear housing, notches cut in the upper end of the shaft housing corresponding to the lower end of the latch lever and adapted to receive same, a clutch control lever secured to the latch lever and moving simultaneously therewith when operated transversely of the housing, but secured to the latch lever by a set screw or bolt which operates as a fulcrum and allows the clutch lever to be operated longitudinally of the gear housing upon the set screw as a fulcrum, a pin mounted in the handle of the

clutch control lever, a compression spring mounted in the handle of the clutch control lever exerting pressure downwardly upon the pin, a plurality of circular seats formed in the housing adapted to engage the lower end of the pin and secure the clutch control lever in position when so engaged. 25

6. In a controlling mechanism for machinery, the combination with a base having a housing rotatably mounted thereon, of a latch lever fulcrumed upon the housing, seats formed in the base adapted to receive and engage a portion of the latch lever, a control lever fulcrumed upon the latch lever moving simultaneously therewith when operated transversely of the housing, but secured to the latch lever by a pivot which operates as a fulcrum and allows the control lever to be 30 35 40 operated longitudinally of the gear housing upon the pivot as a fulcrum.

In testimony whereof, I affix my signature.
HARRY J. CRINER.
